UNITED STATES PATENT OFFICE.

COLEMAN S. WINCHESTER AND JOHN BURTON, OF BROCKTON, MASSACHUSETTS.

DOOR AND WINDOW SCREEN.

Application filed July 28, 1922. Serial No. 578,060.

To all whom it may concern:

Be it known that we, COLEMAN S. WINCHESTER and JOHN BURTON, citizens of the United States, residing at Brockton, in the county of Plymouth and State of Massachusetts, have invented new and useful Improvements in Door and Window Screens, of which the following is a specification.

The object of this invention is to provide a screen, the frame member of which is constructed to releasably confine the woven wire member in such manner that the wire member, when rendered useless, may be conveniently removed and replaced by a fresh member, by a person unskilled in the art of nailing the wire member to the frame member.

The invention is embodied in the improvements hereinafter described and claimed.

Of the accompanying drawings forming a part of this specification,—

Figure 1 is a side elevation of a portion of a screen door in which the invention is embodied.

Figure 2 is a section on line 2—2 of Figure 1.

Figures 3 and 4 show separately in section, the parts shown assembled by Figure 2.

Figure 5 is a fragmentary perspective view, showing a portion of the inner frame section, the wire cloth member being removed.

Figure 6 is a view similar to Figure 5, showing the wire cloth member engaged with the inner frame section.

Figure 7 is a side elevation of a window screen embodying the invention.

Figure 8 is a fragmentary perspective sectional view, the section being on line 8—8 of Figure 7.

Figure 9 is a section on line 9—9 of Figure 7.

Figure 10 is a side view of one of the spurs shown by Figures 2, 5, 6, and 8.

Figures 11 and 12 are views similar to Figure 9, showing modifications.

The same reference characters indicate the same parts in all of the figures.

Referring first, to Figures 1 to 6, inclusive, showing the invention embodied in a screen door, 12 represents an inner frame section of rectangular form. Projecting from one of the side faces of the section 12 are metal spurs 13, adapted, as shown by Figures 4 and 6, to engage meshes in the marginal portion of a filling sheet 15. The spurs are

preferably hook shaped at their outer ends and may be of wire, and drawn into the section 12 with their hooked ends projecting. The spurs are so formed and arranged that the sheet 15 may be conveniently impaled thereon, and held thereby against the side of the section, the hooked form of the spurs causing the outer ends to overhang the sheet, so that the sheet is not liable to slip off from the spurs when the inner section 12 is being handled to engage it with the outer frame section hereinafter described.

16 represents an outer frame section, which in this instance, is the frame or body portion of a screen door, adapted to cooperate with a plurality of inner frame sections 12, each of which constitutes a panel, occupying an opening in the body or outer frame 16. The said inner frame sections are duplicates of each other, so that the part 16 will be hereinafter referred to as an outer frame section, cooperating with an inner frame section 12. The outer frame section 16 has an opening 17 (Figure 3) which receives and closely fits the margin of the inner section 12, and a flange 18, surrounding the opening 17, and projecting inward from the margin thereof. The inner side of said flange forms a seat, adapted as shown by Figure 2, to clamp the marginal portion of the sheet 15 against the face of the inner section from which the spurs 13 project. The flange 18 may be attached to the outer frame section 16 by nails or screws, or by any other suitable means. The inner side of the flange 18 is recessed at 19, to receive the projecting portions of the spurs 13, as shown by Figure 2. We provide means for detachably securing the inner section 12 to the outer section 16, said means being embodied, in this instance, in an outwardly projecting flange 20, attached as by screws 21 to the inner section 12, and overlapping the outer section, and screws 22 attaching the flange 20 to the outer section.

In assembling the described parts, the operator first engages the sheet 15 with the spurs 13, then inserts the inner section in the opening in the outer section until the marginal portion of the sheet is pressed against the seat formed by the flange 18, and the outer ends of the spurs enter the recess 19. The screws 22 are then driven and confine the inner section and the sheet 15 in place in the outer section. When the sheet 15 requires renewal, the screws 21 are withdrawn,

the inner section is removed, a fresh sheet is applied to the spurs, and the inner section is replaced and again secured.

It will be seen that an unskilled person is enabled to remove and replace a screen sheet expeditiously and satisfactorily, the operation of impaling the sheet on the spurs requiring no tools, and the sheet being securely confined by the simple operation of securing the inner section 12 to the outer section 16.

Figures 7 to 9, inclusive, show a window screen embodying the invention. In this embodiment 25 represents the inner frame section from one side face of which project the spurs 13. The outer frame section 26 is rebated, as shown by Figures 8 and 9, to receive the inner section 25, and form a seat 27, between which and the inner section 25 the marginal portion of the sheet 15 is clamped. The outer section 26 is recessed at 28 to receive the spurs 13.

To detachably connect the sections 25 and 26, we provide sheet metal clamping members, bestriding and frictionally engaged with the assembled sections, as shown by Figures 8 and 9, and adapted to run with the screen in the usual screen guides in a window frame. As here shown, these clamping members include two U-shaped members 30, embracing portions of the frame between its ends, and two elongated members which are slidable on the end portions of the frame, and constitute adjustable extensions whereby the length of the frame may be varied. Each of said elongated members includes a central portion 31, extending across the frame, and bearing on one side thereof, neck portions 32 at the opposite ends of the central portion, ears 33 connected with the central portion by the neck portions, and a stop flange 34, formed on the central portion and adapted to abut against the end of the frame.

Each of the said clamping members frictionally engages the frame with sufficient force to move therewith, and is adapted to be removed to permit the separation of the frame sections.

Figures 11 and 12 show modified forms of the spurs, Figure 11 showing a straight spur 13^a, driven obliquely into the inner frame section, so that it is the equivalent of a hooked spur. Figure 12 shows a straight spur 13^b, standing at right angles with the face from which it projects. The hooked form is preferred, because it prevents the sheet 15 from slipping outward from the spur.

We claim:

1. A screen frame comprising an inner frame section having screen cloth-engaging spurs projecting from its inner side face, the spurs being adapted to engage meshes of a foraminous sheet, an outer frame section which is rebated to receive the inner section and form a clamping face, adapted to confine the marginal portion of a sheet of screen cloth against the inner side of the inner section, said clamping face being recessed to receive the projecting portions of said spurs, and sheet metal clamping members detachably connecting said sections, and adapted to run therewith in guides in a window casing.

2. A screen frame comprising an inner frame section having screen cloth-engaging spurs projecting from its inner side face, the spurs being adapted to engage meshes of a foraminous sheet, an outer frame section which is rebated to receive the inner section and form a clamping face, adapted to confine the marginal portion of a sheet of screen cloth against the inner side of the inner section, said clamping face being recessed to receive the projecting portions of said spurs, and sheet metal clamping members detachably connecting said sections, and adapted to run therewith in guides in a window casing, two of said clamping members being slidably on the end portions of the assembled sections, and formed to constitute adjustable extensions thereof.

In testimony whereof we have affixed our signatures.

COLEMAN S. WINCHESTER.
JOHN BURTON.
